UNITED STATES PATENT OFFICE

BENJAMIN F. PERKINS, OF HOLYOKE, MASSACHUSETTS

DESIGN FOR A BODY FOR AUTOMOBILES OR THE LIKE

Application filed August 2, 1929. Serial No. 32,276. Term of patent 7 years.

To all whom it may concern:

Be it known that I, BENJAMIN F. PERKINS, a citizen of the United States, residing at Holyoke, in the county of Hampden and State of Massachusetts, have invented a new, original, and ornamental Design for Body for Automobiles or the Like, of which the following is a specification, reference being had to the accompanying drawing, forming part thereof.

Fig. 1 is a side elevational view of a body

for an automobile or the like showing my new design.

Fig. 2 is an end elevational view of the same.

The dominant feature of my design consists in the panel arrangement on the sides and rear of the body.

I claim:

The ornamental design for a body for automobiles or the like as shown and described.

BENJAMIN F. PERKINS.
